MOLDING STRIP

Edward K. Pilcher, Detroit, Mich., assignor to
 Bohn Aluminum & Brass Corporation, Detroit,
 Mich., a corporation of Michigan

Application July 11, 1936, Serial No. 90,245

12 Claims. (Cl. 20—74)

This invention relates to molding strips adapted to conceal a line of fastening devices, such as nails or the like, and to present a smooth finished appearance.

5 The improved molding is particularly adapted to covering the joints of motor vehicle bodies, but quite obviously it can be used wherever need for such a molding arises.

A chief object of the invention is to provide an 10 all-metal molding which can be applied with a minimum of labor, which forms a permanent weather-tight joint, and which has a pleasing ornamental appearance.

15 These and other objects and advantages of the invention will become apparent as the description proceeds.

20 While preferred forms of the invention are disclosed for purposes of illustration, it should be understood that various changes may be made without departing from the spirit of the invention as herein set forth and claimed.

In the drawing:

Fig. 1 is a cross section through a body strip embodying the invention.

25 Fig. 2 is a cross section through a cover strip adapted to cooperate with the body strip of Fig. 1.

Fig. 3 is a cross section showing the parts in installed position.

30 Fig. 4 is a perspective of the molding shown in Fig. 2.

Fig. 5 is a cross section showing a modified form of the invention.

The molding of the invention has for its principal parts a body 10 and a cover strip 11. The 35 body has a channel formed with vertical side walls 12 and a bottom wall 13. The cover strip is of such a size that its vertical side walls 14 have a close frictional fit with the walls 12 of the body. The body and cover strip are preferably formed 40 by extrusion from some relatively soft metal, such as an alloy of aluminum. The extrusion process produces strips formed of "worked-metal", with a grain structure running lengthwise of the strip, thus permitting ready bending of the strip in any 45 direction to conform to the contour of the structure to which the molding is being attached. The extrusion process also produces minute ridges running longitudinally of the strips as the result of unavoidable irregularities of the extrusion dies. 50 These extrusion ridges are shown on an exaggerated scale in the drawing. After the body 10 has been mounted in place, in a manner that will be explained shortly, the cover strip is pressed into the channel of the body 10, and these minute 55 extrusion ridges together with the relatively soft

malleable character of the metal forming the body 10 and cover strip 11 form a tight frictional fit that holds the strip firmly in place.

To secure a still tighter fit of the cover strip within the channel, the preferred form of the 5 invention provides deformable fins 15 on the side walls 12 of the channel or on the walls 14 of the cover strip, or on both walls 12 and 14, the latter form being illustrated in Fig. 1. These fins 15 being very small are easily deformable and they 10 do not interfere with tapping the cover strip into place by light blows of a hammer. During this operation the fins 15 are partly deformed and partly sheared away, thus compensating for any irregularities in the engaging walls 12 and 14 and 15 forming a close weather-tight joint between said walls.

The bottom wall 13 of body 10 is formed with a central groove 16. The moldings are usually fastened in place by nails and the groove 16 forms 20 a central line for aligning the nails and sufficiently weakens the bottom wall of the channel to permit the nails to be easily driven through wherever desired. This arrangement is more advantageous than punching holes for the nails, 25 since it is less expensive to produce and it permits placing a nail wherever desired in order to catch a supporting member or to space the nails more closely together when bending the molding sideways around a curve. 30

Extending laterally from body 10 are wings 17, the upper surfaces of which are curved on an arc struck from below the body and which terminate in lower edges 18 without curving inwardly toward the body. The edges 18 are relatively 35 sharp and project downwardly below the level of the bottom wall 13 of body 10, as clearly shown in Fig. 1. The undersides of wings 17 may be given any suitable contour to lighten the molding 40 and save metal.

The manner of attaching the strip is clearly 45 illustrated in Fig. 2 where it is used to cover an overlapping joint of two pieces of fabric 20 and 21 on a support member 22. The molding strip is aligned with its channel directly above the overlapping joint and it is then secured in place by driving nails or other suitable fastening elements 23 into groove 16. As the body is nailed down, the lower edges 18 are pressed firmly into the fabric and hold it tightly against the support 22, forming a secure weather-tight joint. Due to the fact that the edges 18 are at the outer extremities of the molding, the upper curved surface of wings 17 form obtuse angles with the 55

fabric, avoiding any acute angle that would have to be filled in with plastic cement.

During the operation of nailing the body down, the pressure of edges 18 against the support 22 serves not only to form a secure joint with the fabric, but a leverage action causes the upper ends of wings 17 to move the upper corners of the walls 12 of the channel slightly towards each other.

- 10 After the body 10 has been nailed in place the cover strip 11 is placed in the channel and driven home, deforming the fins 15 as previously explained and wedging the upper corners of the walls 12 back to vertical position. When the 15 parts have reached their final assembled positions the walls 14 of the cover strip have made a perfect lapped-in seal against the walls 12 of the channel, and the supporting pressure of the wings 17 holds them resiliently in place against 20 any possible loosening effects of expansion, vibration, etc.

The body 10 and cover strip 11 carry cooperating surfaces which hold the central part of the bottom wall 24 of the cover strip spaced 25 above the bottom wall 13 of the channel in order to provide clearance for the heads of the nails. In the form of the invention illustrated in Figs. 1 and 2 this object is achieved by giving bottom wall 24 of the cover strip an upwardly curved 30 contour forming shoulders 25 at the side of wall 24 which engage with the bottom 13 of the channel. In the form illustrated in Fig. 4 shoulders 26 are formed on the side walls of the channel. These parts are so designed as to predetermine 35 the final position of the cover strip, which in the form shown has its upper surface flush with the upper surface of body 10.

In the form illustrated in Figs. 1 to 3 the outer surface of the molding has a semi-circular contour, but it should be understood that this outer surface can be given any desired ornamental or utilitarian shape. For example, as shown in Fig. 4 the molding is mounted in a vertical position on the side of a support 27 and the lower 45 part of the molding carries a drip trough 28.

Those skilled in the art will appreciate that this molding can be economically manufactured and installed, and that its all-metal construction furnishes a permanent covering that needs no 50 subsequent servicing.

I claim:

1. A molding comprising a body formed of extruded metal with a channel therein having vertical side walls with minute extrusion ridges 55 extending longitudinally of the molding, a cover strip formed of extruded metal of a shape to fit closely between the side walls of the body, the cover strip having vertical side walls with minute extrusion ridges extending longitudinally of the 60 molding and adapted to engage the ridges of the channel walls to assist in holding the cover strip in place in the channel.

2. A device as recited in claim 1 in which deformable longitudinal fins are carried by the 65 vertical walls of the channel.

3. A device as recited in claim 1 in which deformable longitudinal fins are carried by the side walls of the cover strip.

4. A device as recited in claim 1 in which deformable longitudinal fins are carried by the 70 vertical walls of the channel and by the side walls of the cover strip.

5. A molding comprising a body of solid metal having a channel with vertical side walls formed therein, the bottom of the channel being formed with a central groove forming a weakened portion adapted to be pierced by nails, a metal cover strip fitting in the channel, and cooperating surfaces on the body and cover strip for holding the cover strip out of contact with the nails. 5

6. A device as recited in claim 5 in which deformable longitudinal fins are carried by the 10 vertical walls of the channel.

7. A device as recited in claim 5 in which deformable longitudinal fins are carried by the side walls of the cover strip.

8. A device as recited in claim 5 in which deformable longitudinal fins are carried by the 15 vertical walls of the channel and by the side walls of the cover strip.

9. A molding comprising a body of solid malleable metal having a channel with vertical side 20 walls formed therein, a metal cover strip having vertical side walls frictionally engaging with the side walls of the channel, at least one side of said body carrying a laterally extending wing 25 the upper surface of which curves downwardly and outwardly from the body and which terminates in a relatively sharp edge lying below the bottom of said body.

10. A device as recited in claim 9 in which one 30 of said wings extends from each side of said body respectively.

11. In combination, a support, two pieces of covering material forming an overlapping joint on said support, a molding comprising a metal body overlying said joint, said body being formed 35 with a channel having vertical side walls, the bottom wall of said channel being formed with a groove, fastening devices extending into said groove and through the bottom wall of the channel into the support, a metal cover strip fitting 40 in said channel and being held in place solely by frictional engagement with the side walls of the channel, a wing extending outwardly and downwardly from each side of said body respectively and terminating in a relatively sharp edge 45 pressing the fabric firmly against the support, the angle between the outer surface of the wing and the fabric being an obtuse angle, the pressure of the sharp edges of the wings against the support causing the base of the wings to hold 50 the sides of the channel firmly against the cover strip.

12. A molding comprising a body and a cover strip formed of aluminum alloy, the body being extruded with laterally extending wings, with a 55 channel having vertical side walls, and a groove formed in its bottom wall, and with deformable longitudinal fins on the side walls of the channel, the cover strip being extruded with vertical side walls adapted to frictionally engage the side 60 walls of the channel and carrying deformable longitudinal fins, cooperating surfaces on the body and cover strip for holding the central part of the cover strip spaced from the bottom wall of the channel, each of said wings extending outwardly and downwardly from the upper part of the body and terminating in a relatively sharp corner located below the bottom of the body, the underside of each wing being concave. 65
